FIGURE TOY

George R. O'Neal, Washington, D. C., assignor to
 George H. Hutaft, Jr., Wilmington, N. C.

Application April 5, 1937, Serial No. 135,161

1 Claim. (Cl. 46—107)

The invention relates to a figure toy and more especially to figure wheeled toys.

The primary object of the invention is the provision of a toy of this character, wherein an image imitative of a living rabbit will be mechanically operated to effect motion to such image when the toy is rolled upon a foundation or surface and the motion simulates the jumping of the rabbit while on the run.

Another object of the invention is the provision of a toy of this character, wherein the image in its construction is of novel form and the motion thereto is imparted in a novel manner, the toy being attractive in appearance and lends amusement to children due to the motional characteristics of such image when being pulled or pushed in the traction of the same.

A further object of the invention is the provision of a toy of this character, which is simple in construction, thoroughly reliable and efficient in operation, ornamental in its make-up, strong, durable, and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claims hereunto appended.

In the accompanying drawing:

Figure 1 is a side elevation partly in vertical section of the toy constructed in accordance with the invention.

Figure 2 is a top plan view partly broken away.

Figure 3 is a fragmentary vertical sectional view through the image of the toy.

Figure 4 is a fragmentary rear elevation partly in section.

Similar reference characters indicate corresponding parts throughout the several views in the drawing.

Referring to the drawing in detail, the toy comprises a wheeled carriage involving a body 10 preferably flat and having depending from its bottom next to the opposite longer side edges thereof sills 11, these being formed with front and rear bearings 12 and 13, respectively, in which are journaled the front and rear axles 14 and 15 for the traction wheels 16, these being fixed to the ends of said axles outside of the sills 11. The rearmost axle 15 is formed with a crank 17 for a purpose presently described.

Above the carriage, that is, the body 10 thereof, is an image, in this instance being representative of a rabbit, its body 18 at opposite

sides thereof has swingingly connected thereto pairs of front and rear legs 19 and 20, respectively, which by pivot shafts 21 are connected to the body 10 of the carriage for rocking movements, the body 10 of the carriage being formed with fore and aft clearance slots 22 and 23, respectively, for accommodating the said legs 19 and 20. The legs 20 are formed with bifurcated extensions or forks 24 accommodating therein the crank 17 of the rear axle 15 so that when this axle is turned by the traction of the rear wheels 16 motion is transferred from the crank 17 to the rear legs 20, these legs 19 and 20 are pivoted at 25 to the body 18 of the image and thus motion will be imparted to the latter simulating a jumping rabbit when on the run.

The body 18 at its rear is provided with a tail stub 26 while carried at the neck formation 27 of the body 18 of the image is a vertically swinging or turnable head 28 rotatable on a horizontal axis created by a pair of screws 29 threaded transversely through the head 28 from opposite sides thereof and made fast in the neck formation 27. This neck formation 27 has provided therein the cutaway portions 30 and 31, respectively, while the head is formed with the recess 32 centrally therein and opening through the rear edge portion of said head. The cutaway portion 30 affords an overlap 33 for the crown 30 or upper portion of the head 28. This head 28 is provided with ears 34.

The cutaway portion 31 opens fore of the body 18 but does not open through opposite sides of said body. Accommodated within the cutaway portion 31 and the recess 32 is a link 35 which at the forward end thereof is attached to the head 28 by a transverse pivot 36 and at the rear end is eccentrically attached to the front pair of legs 19 with respect to their pivot 25 by a transverse pivot 31, the latter working in an arcuate slot 38 provided in the body 18 at each side of the cutaway portion 31 therein. Thus when motion is set up in the front legs 19, the link 35 becomes active upon the head 28 to turn 45 the same on the pivot 29.

In the operation of the toy through traction of the wheels 16, that is to say, the rearmost wheels, the rear axle 15 on the turning thereof through its crank 17 oscillates the rear legs 20 thus imparting motion to the body 18 of the image and this motion through the front legs 19 actuates the head 28 causing it to swing vertically on the horizontal pivot 29 and such motions imparted to the body 18 of the image cause 55

the latter to imitate the hopping characteristic of a live rabbit when on the run.

The body 10 of the carriage has fixed in its forward end a staple 39 to which is attached 5 a pull cord or string 40 so that the toy may be drawn or pulled in a forward direction for traction activity of such toy.

What is claimed is:

10 A figure toy of the character described, comprising a wheeled carriage, including a rear crank shaft, adapted to be propelled over a surface and an image simulating an animal having the characteristic jumping action of a rabbit on the run, said image including a body member having an 15 arcuate opening adjacent its forward end, a head member pivotally mounted on the forward portion of the body member, a pair of front legs pivotally mounted at their lower ends to the carriage and at their upper ends to the forward 20 portion of the body member, a link pivotally connected at one end to the head member and at

its opposite end pivotally connected to the front legs, said last-mentioned pivotal connection passing through and operable in the arcuate opening in the body member, and a pair of rear legs pivotally connected at their upper ends to the 5 body member and adjacent their lower ends to the carriage, the portion of the rear legs below their pivotal connection to the carriage forming extensions forked at their ends to receive the crank portion of the rear shaft, the movement 10 of the carriage over the surface operating the rear crank shaft to swing the rear legs on their pivotal connections with the carriage and operate the body member relative to the carriage and simultaneously raise the forward end of the 15 body member and the head member as the body member is moved forwardly relative to the carriage and to lower the body member and head member when the body member is moved rearwardly relative to the carriage.

20

GEORGE R. O'NEAL.
